CAN LIFTER

Filed Sept. 17, 1929

INVENTOR.

Mr. Cap

BY

ATTORNEY.

UNITED STATES PATENT OFFICE

WILLIAM E. CULP, OF MONON, INDIANA

CAN LIFTER

Application filed September 17, 1929. Serial No. 393,149.

The invention relates to can lifters, and has for its object to provide a device of this character having crossed U-shaped handles formed from relatively heavy wire, and provided with registering eyes beneath their crossing point, and a pivot bar extending through said eyes, said eyes terminating in downwardly extending substantially U-shaped gripping jaws adapted to engage 10 opposite sides of a can or of a receptacle.

A further object is to form the U-shaped handle members, the eyes carried by the arms thereof and the U-shaped jaws from a single piece of material bent to form.

15 A further object is to form the pivot bar from a piece of rod material bent to form loops engaging the inner eyes of the pivoted members and the hooked portions extending through the eyes of the pivoted members for 20 pivotally connecting the eyes together.

With the above and other objects in view the invention resides in the combination and arrangement of parts as hereinafter set forth, shown in the drawing, described and claimed, 25 it being understood that changes in the precise embodiment of the invention may be made within the scope of what is claimed without departing from the spirit of the invention.

30 In the drawing:

Figure 1 is a perspective view of the lifter.

Figure 2 is a horizontal sectional view taken on line 2—2 of Figure 1.

Figure 3 is a perspective view of one of 35 the combined handle and jaw members of the lifter.

Figure 4 is a vertical transverse sectional view through the central portion of the lifter.

Referring to the drawing, the numeral 1 40 designates the U-shaped handle members of the lifter, which members are in crossed relation at A as clearly shown in Figure 1. The arms 2 of the handle members extend downwardly and are bent to form eyes 3, 45 which register with each other and extend inwardly to receive the hooked ends 4 of the pivot bar 5. Pivoted bar 5, adjacent its hooked ends 4, is bent to form eyes 6, which engage the inner sides of the inner eyes 3

50 as clearly shown in Figure 2 and maintain

the eyes in relatively close position during a jar lifting operation, at which time the handle members are forced together by the operator grasping the transverse portions 7 thereof. The single wire from which the movable parts are formed preferably terminate at 8 in the handle members 7.

Extending downwardly from the eyes 3, and at an angle to the U-shaped handle members 1 are U-shaped jaws 9, which are formed from the same piece of material and have their lower ends bent to form horizontal jar or can engaging members 10.

In operation the operator spreads the 55 handle members 1 which are in crossed relation, and which action spreads the gripping jaws 9 so a jar or can can be received between the arcuate portions 10 of the device. After placing the device over a can or jar the operator grasps both transverse members 7 of

60 the handles and forces the same together, thereby forcing the arcuate members 10 into close binding engagement with opposite sides of a can or other receptacle, therefore it will be seen that receptacles will be easily handled particularly when hot as in canning. It will

65 be seen that the device is formed from relatively heavy wire bent to form, thereby reducing the cost of manufacture to a minimum and allowing the device to be constructed by relatively cheap labor. Handle members 7 are preferably provided with a wire wrapping 11 formed from relatively small wire so as to increase the diameter of 70 the gripping members, thereby increasing the gripping power which the operator may place on the device.

75 The invention having been set forth what is claimed as new and useful is:—

80 A jar lifter comprising pivoted members, 85 said members having opposite arms, registering eyes carried by said opposite arms, a pivot bar extending through said eyes, said pivot bar terminating in hooked members to the outside of the registering eyes, said bar having eyes therein disposed to the inside of the registering eyes.

90 In testimony whereof he hereunto affixes his signature.

100 WILLIAM E. CULP.
